SAFETY BOX STRUCTURE

Robert D. McBride, Minneapolis, Minn.

Application March 16, 1946, Serial No. 654,906

3 Claims. (Cl. 109—52)

1

This invention relates to a safety box structure and while the invention might have various applications it particularly is designed for use in homes, offices or small stores, etc. It is often desirable to have a strong box or safety box in a residence in which jewelry and other valuables can be kept, which box can be disposed or placed in an inconspicuous location. Such a box is also desirable in an office, small store or the like, where the amount of cash or valuables on hand does not warrant the possession of a regular large safe.

It is an object of this invention to provide a simple, strong and efficient structure of safety box which can be placed in a hidden or inconspicuous location, and one which is preferably fireproof.

It is a further object of the invention to provide a safety box comprising simple and effective means by which it can be secured to a floor.

It is another object of the invention to provide a safety box comprising a locking means secured to a floor, means on said box cooperating with said locking means and movable into cooperating relation therewith by a longitudinal movement of said box, a pin preferably being provided extending through said box and into the floor for preventing longitudinal movement of said box to disengage said locking means.

It is a further object of the invention to provide a safety box structure comprising a casing preferably of rectangular form in cross section, said casing having a chamber therein open at one end and a door of novel construction fitting in and closing said end.

These and other objects and advantages on the invention will be fully set forth in the following description made in connection with the accompanying drawings in which like reference characters refer to similar parts throughout the several views and in which—

Fig. 1 is a vertical section taken substantially on line 1—1 of Fig. 4;

Fig. 2 is a vertical section taken substantially on line 2—2 of Fig. 4;

Fig. 3 is a vertical section similar to Fig. 1 showing parts in different positions;

Fig. 4 is a view in front elevation of the device;

Fig. 5 is a horizontal section taken substantially on line 5—5 of Fig. 4;

Fig. 6 is a plan view of locking members used with the casing of the device removed;

Fig. 7 is a horizontal section taken on line 7—7 of Fig. 8;

Fig. 8 is a partial vertical section taken on line 55

2

8—8 of Fig. 7, all of said sections being taken as indicated by the arrows; and

Fig. 9 is a view in front elevation of the device with the door removed.

5 Referring to the drawings, a device is shown comprising a plate 10 of comparatively small thickness which will engage the top of a floor 11, such as a concrete floor. Members 12 are secured to plate 10 and floor 11, and while these 10 might vary in form, in the embodiment of the invention illustrated they are shown as spaced plate-like bars extending transversely across plate 10, which plate, as shown in Fig. 6, is of somewhat elongated rectangular form. The bars 12 are spaced above plate 10 by spacing washers 13 and securing headed bolts 14 extend through bars 12 and members 13 and 10 into the floor 11, as shown in Figs. 1 and 8. A casing 16 is provided and while this casing might take various forms, in the embodiment of the invention illustrated it is shown as rectangular in transverse section and of somewhat elongated form. Casing 16 has an outer wall 16a which will be made of plate-like material, preferably steel, and an inner wall 16b spaced some distance from the outer wall 16a. The space between walls 16a and 16b will contain some filling material such as a good insulating material 17. Wall 16b will preferably be made of sheet metal which may be of lighter gauge than the metal of wall 16a. Wall 16b has a chamber therein open at one end and wall 16b flares outwardly at said open end and has an outer portion 16c extending at right angles to and engaging the side portions of wall 16a. Walls 16a and 16b will preferably be welded into integral pieces and portions 16c will preferably be welded at their outer edges to wall 16a. The vertical side portions of wall 16a are extended downwardly somewhat and have plate-like portions 16d extending inwardly therefrom at their bottoms. (See Figs. 1, 3, 7 and 8.) Other similar but shorter portions 16e also extend inwardly and are spaced some distance from the adjacent ends of members 16d. Members 16d and 16e are 30 in the same plane. The length of the space 16f between members 16e and 16d is slightly greater than the width of bars 12. As illustrated in Fig. 3, it is apparent that casing 16 can be placed with members 16d and 16e resting on plate 10, 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

The sides of wall 16a extend forwardly some distance beyond portions 16c and a plurality of plates 18 are disposed about and in engagement with wall 16a. The inner edge portions of plates 18 are arranged in stepped relation and at the top and sides of wall 16a the innermost plate 18 projects farthest toward the center of said casing. At the bottom side however the outermost plate 18 projects farthest toward the center of the casing. Said outermost plate 18 at the bottom also has its top beveled outwardly, as shown at 18a in Figs. 1 and 2. A door 20 is provided, the same having an outer plate 20a which at its top and sides fits within the top and side portions of wall 16a and at its bottom fits against a plate 16g which extends between the sides of wall 16a and has its front surface flush with the front edges of wall 16a. Plate 16g extends downwardly to the bottom of plates or portions 16e. Door 20 has an inner wall 20b having a tapering portion arranged to fit in the flaring portion of wall 16b. At the top and sides of door 20, wall 20b has a portion 20c extending substantially perpendicular to and engaging the inner side of plate 20a to which it preferably will be welded. The space between plate 20a and wall 20b will also be filled with suitable packing material such as a good insulating material 21. Said door also comprises a plurality of plates 20d which extend about portion 20c in engagement with the outer side thereof and extend across said door at the bottom thereof. Wall 20b at the bottom is bent vertically to engage the inner plate 20d, as shown in Figs. 1 and 2, the top edge of said vertically bent portion being flush with the top edges of plates 20d. The plates 20d engage portion 20c at their inner edges, which edges are in one plane, but the outer edge portions of plates 20d are arranged in stepped relation. At the top and sides the outermost plate 20d extends farthest toward wall 16a. At the bottom of the door however the innermost plate 20d extends farthest toward wall 16a. It will be seen, as shown in Figs. 1 and 2, that the stepped plates 20d fit the stepped plates 18 when the door is in closed position, the inner edges of the plates 18 engaging the outer edges of plates 20d. In the embodiment of the invention illustrated there are three each of the plates 18 and 20d and the two innermost plates 20d at the bottom of the door have their bottom edges rounded, as shown at 20e.

The outwardly flared portion of wall 16b at its bottom is provided with a recess 16h centrally thereof, as shown in Figs. 2 and 5. A headed pin 24 extends through the bottom of wall 16b through the bottom of wall 16a and through plate 10 into floor 11. The head of pin 24 is disposed in recess 16h and is shown as slotted. A lock 25 is provided for door 20 and is secured to plates 20d and to a lug 20f welded to the inner side of plate 20a, by headed screws 27. Lock 25 has a key-receiving portion 25a extending through an opening in plate 20a and having its front surface flush with the front surface of plate 20a. Lock 25 will include one or more tumblers or bolts 25b which can be moved by the key of said lock into position in the rear of the innermost plate 18, as shown in Fig. 2. The chamber 16k in wall 16b will be adapted to hold some receptacle which could be in the form of a box 28 open at its top and having a handle 28a at its front side.

The members 10 and 12 can be placed beneath the floor of a room and be covered with casing

16 by a trap-door or panel, or said members could be placed in the rear of a baseboard in a room or even in a pocket in the wall of a room. The valuables to be stored will be placed in the receptacle 28 and the same disposed in the chamber in wall 16b. Door 20 will then be placed in position by placing the bottom side in the position shown in Figs. 1 and 2 so that plates 20d have their lower portions at the inner sides of plates 18. The door will now be tipped or swung inwardly and come into the position shown in Figs. 1 and 2. The key in lock 25 can now be turned and the tumbler or bolt of said lock will move into position in the rear of innermost plate 18 at the top of the said casing. Before the door 20 is so placed in closed position, however, the casing 16 will be placed on plate 10, as shown in Fig. 3, the spaces 16f accommodating the forward bars 12. The casing will now be pushed rearwardly to the position shown in Fig. 1, and plates 16e will pass under forward bars 12 and plates 16d will pass under the rear bars 12. The casing is now locked against vertical movement. Pin 24 will now be dropped into place as it will be in alignment with the hole in the plate 10 and floor 11. Door 20 will now be closed and locked, as above described. It will be noted that the plates 20d at the bottom will prevent forward movement of the door if lock 25 has been forced or blown out by an explosive. The door does not have side hinges and this might prevent its being opened by any unauthorized person trying to enter the box. When the door is unlocked and swung forwardly, the pin 24 must first be removed before the casing can be moved forwardly to be lifted. Anyone attempting to enter the box illegally might not remove pin 24 and would not know that casing 16 has to be moved forwardly to be lifted. A very strong and secure safety box is thus provided.

From the above description it will be seen that I have provided a simple and very efficient structure of safety box or strong box. The same is adapted to be disposed in a hidden or obscure place. The casing used is locked in position by simple and efficient means and is effectively closed by the door thereof. The chamber 16k is fireproof and well protected by the fireproof insulation material 21. Articles in receptacle 28 would thus be secure against fire. The device can be easily made from simple and easily procured material, the same has been amply demonstrated in actual practice and found to be very successful and efficient.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A safety box structure having in combination, a casing having a chamber therein, laterally spaced inwardly extending members on said casing at the bottom thereof, said members having aligned openings in their adjacent sides, members secured to a floor and spaced above the same, said second mentioned members being of a width to pass through said openings whereby said casing can be moved downwardly so that said second mentioned members can pass through said openings and then move longitudinally to bring portions of said first men-

tioned members beneath said second mentioned members.

2. A safety box structure having in combination, a casing of general rectangular form in transverse section, plate-like strips spaced longitudinally of said casing and extending transversely thereof, means securing said strips to a floor, means between said strips and floor spacing said strips slightly above said floor, said casing having inwardly extending narrow plates at each side thereof at its bottom, said plates respectively having openings therein through which said strips can pass whereby said plates can be disposed below said strips and said casing can be moved longitudinally to bring said plates beneath said strips.

3. The structure set forth in claim 1, and a headed pin extending downwardly from said casing and through one of said second mentioned

members into the said floor, said pin being freely removable vertically.

ROBERT D. McBRIDE.
